UNITED STATES PATENT OFFICE

2,567,619

ADJUSTABLE BED

Edward M. Rosenfeld, Cleveland Heights, Ohio;
 Sylvia Rosenfeld, administratrix of said Edward
 M. Rosenfeld, deceased, assignor to Sylvia
 Rosenfeld

Application February 18, 1946, Serial No. 648,283

2 Claims. (Cl. 5—181)

1

The present invention relates generally to beds and more particularly to adjustable beds without the usual head and foot portions for conversion into single, three-quarter or double beds.

Heretofore, adjustable beds have usually all been of a type having an upstanding head and foot portion. To provide for adjusting these beds it is necessary to have the head and foot portions adjustable as well as the bed frame, which supports the bed spring. In making the upstanding head and foot portions adjustable a complicated arrangement is necessary and this type of bed when thus made adjustable has been found to be very impractical due to these head and foot portions. Accordingly, I have provided an adjustable bed of the so-called "Hollywood" type, a bed having only supporting legs, and a frame without the aforementioned upstanding head and foot portions.

An object of my invention is to provide a novel bed comprised of one standard set of elements which are all of the same size regardless of whether the bed when sold is to be single, three-quarter or double.

Another object is to provide a novel bed of the so-called "Hollywood" type, which is easily adjusted to any width spring or mattress.

Another object is to provide a novel bed adapted to be readily knocked down into several parts for convenient storage in a small closet or the like.

Still another object is to provide all rounded corners on the frame to thereby eliminate the sharp corners likely to cause injury to a person striking against them.

Further objects and advantages of my novel adjustable bed will be apparent from the following description of one embodiment of my invention, wherein the reference numerals refer to the several parts as illustrated in the accompanying drawings by like numerals. It is to be understood, however, that the present description and drawings are for the purposes of illustration and are not intended to limit the scope of my invention, reference for this purpose should be had to the appended claims.

In the drawings:

Figure 1 is a perspective view of my novel bed frame with springs and mattress removed.

Figure 2 is a view of one of the side rails of the frame with a section of one end rail attached.

Figure 3 is an isometric view of the second section of the adjustable end rails.

Figure 4 is an outside view partly in elevation

2

and partly in section of one of the four corner brackets which carry the bed legs, and

Figure 5 is an inside view of the corner brackets. Referring in detail to the several figures of the drawings and first with particular reference to Figure 1, there is illustrated one embodiment of my invention comprising a bed frame 10, four supporting legs 11, and four corner brackets 12 having inverted cup portions 13 within each of which is mounted and secured one of the legs 11.

The bed frame 10 is of novel construction and comprises a pair of side rails 15 and 16 connected together at each end by a pair of extensible end rails 17 and 18. These rails 15, 16, 17 and 18 are preferably made from angle iron material positioned so as to provide a land or flange 20 exteriorly bounded by the upstanding flange 21 of the angle iron to support a bed spring, not shown. Each end of each side and end rail is so shaped and so formed as to provide four round corners where they connect together. For example, as shown in Figure 3, each end rail 17 and 18, comprises two sections 22 and 23 having the land 20 cut back from the end of upstanding flange 21, which flange 21 is curved inwardly in a lip 24, so as to have its end abut with the end 25 of flange 21 of an adjacent side rail 15 or 16 and thus provide a smooth rounded corner.

The rounded corners of the frame 10 when assembled are arranged to nest within the corner brackets 12. Each corner bracket 12, as shown in Figure 5, is provided with a horizontal supporting surface 30 from the rear of which extends vertically at substantially right angles a flange 31. The bracket 12 is rounded with a curve 32 complementary to the rounded corner defined from the end lip 24 of the respective end rails 17 and 18 and the abutting end 25 of the respective side rails 15 and 16. These brackets are secured to the angle iron rails by the rivet 26 and the lock bolt 27, which both penetrate through the surface 30 as well as the ends of the frame rails.

At each corner the lands 20 of the side and end rail sections overlap and are thus pivoted on the rivet 26 with the bracket 12. In alignment with each rivet 26 are threaded openings through the lands 20 of the rails for receiving the lock bolt 27 to lock the rail members and bracket together and prevent any pivotal movement until the bolt 27 is removed.

The end rails 17 and 18 at each end of frame 10 have their sections 22 and 23 lapped over each other, and the upper rail 22 is provided with round

55 other, and the upper rail 22 is provided with round

bolt receiving apertures 28, while the lower rail 23 is provided with longitudinal slots 29.

These apertures 28 and slots 29 are preferably three in number in each rail section and are arranged to be selectively registered for adjusting the frame to any of three different standard widths. After such adjustment for size has been made bolts of suitable size are put through aligned apertures and slots to lock the sections together to the adjusted position. The slots 29 are of a predetermined length to allow for any slight difference in width between bed springs.

When the bolts 27 are removed from the outer ends and the lapping inner ends of the sections 22 and 23 of each end rail 17 and 18 each of such sections may be pivoted around a rivet 26 and folded into side by side relation with the side rail to which it is connected by the rivet 26, for shipment or storage.

Though my invention relates more to a bed frame without a headboard or footboard, nevertheless, if desired, headboard and footboards for different sizes of beds may be purchased and secured to the frame on the head and foot of the same. For this purpose I have provided bolt holes 33 at each end of the frame 10, whereby a headboard and footboard, not shown, may be secured thereto if desired.

Thus I have provided a novel adjustable knock-down bed adapted to be sold as a standard product for use either as a single, three-quarter or double bed. Also this bed may be folded up and stored in a minimum amount of space so as to make it practical for use in apartments or where there is not room for an extra bed to be set up at all times.

Although only one embodiment of the invention has been illustrated and described in detail, it is to be understood that various changes may be made within the scope of the appended claims by others skilled in the art, and accordingly to determine the scope of the invention reference should be had to the appended claims.

I claim:

1. In a laterally adjustable bed structure, an oblong frame comprising two identical U-shaped longitudinal sections including side rails and end rail sections formed of angle iron of L-shaped cross-section, said end rail sections being disposed in overlapping relation with each other and having the overlapping portions of the horizontal

flanges thereof provided with a plurality of equidistantly spaced openings, and securing means, such as bolts and the like, selectively engaged in said openings, the said end rail sections being made separate from said side rails and the outer ends of the horizontal flanges thereof being detachably secured to the underlying ends of the like flanges of the side rails, the outer ends of the vertical flanges of said end rail sections being curved into abutting relation with respect to the adjacent ends of the like flanges of the side rails.

2. In a laterally adjustable bed structure, an oblong frame comprising two identical U-shaped longitudinal sections including side rails and end rail sections formed of angle iron of L-shaped cross-section, said end rail sections being disposed in overlapping relation with each other and having the overlapping portions of the horizontal flanges thereof provided with a plurality of equidistantly spaced openings, and securing means, such as bolts and the like, selectively engaged in said openings, the corners of said frame sections being rounded, angled leg supporting brackets, also formed of angle iron of L-shaped cross-section, engaged about the outer sides of said corners with the horizontal flanges thereof underlying the same, and means, in the form of bolts and the like, for securing the ends of the vertical flanges of said brackets to the like flanges of said side rails and end rail sections of the frame.

EDWARD M. ROSENFELD.
